GATE SUPPORT

Filed Jan. 20, 1926

UNITED STATES PATENT OFFICE.

HARRIS BURT HOLBROOK, OF METROPOLIS, NEVADA.

GATE SUPPORT.

Application filed January 20, 1926. Serial No. 82,572.

This invention relates to improvements in gate supporting apparatus and has for its primary object to provide a gate support of adjustable character so that the position of 5 a gate relative to the ground or floor may be conveniently regulated.

Another object of the invention is the provision of a gate support of the above type designed to permit substantial vertical movement of the gate so that the gate may be conveniently operated under various weather conditions, such as a snow fall, or, to overcome distortion of the gate frame.

Still another object of the invention is the 15 provision of a supporting apparatus of the above character which is simple yet durable of construction and may be sold at a comparatively low cost.

Other objects and advantages of the invention will become apparent as the description progresses.

In the accompanying drawing forming a part of this specification and in which like reference characters are employed to designate corresponding parts throughout the same:

Figure 1 is a side elevation of my improved apparatus shown in operative position in association with a gate and gate supporting post.

Figure 2 is an enlarged vertical sectional view through the supporting structure, and

Figure 3 is a transverse sectional view taken on the line 3—3 of Figure 1.

As is well known to those familiar with this art, farm gates are usually mounted on a vertically aligned hinge support so that the gate may be conveniently swung in a horizontal arc. Various types of supporting structures are employed for this purpose and are customarily arranged so that the lower edge of the gate is positioned slightly above the ground, sufficient to permit clearance while swinging the gate and at the same time prevent the escape of fowl and the like. When, however, the ground adjacent the gate is covered with snow it is necessary to exert unusual pressure against the gate to open the same or, entirely elevate the gate supporting mechanism. This of course, necessitates a substantial amount of time and labor in order that the gate may be arranged in proper position.

With this in mind, my improved apparatus provides a structure of adjustable char-

acter arranged so that comparatively slight turning movement of a hand wheel or bolt will adjust the vertical position of the gate in conformity to the existing conditions.

With reference to the drawing, wherein 60 for the purpose of illustration is shown the preferred embodiment of my invention, the numeral 5 generally indicates a conventional type of gate such as is commonly employed on farms. The gate is usually of longitudinal rectangular formation and may embody a strip of wire secured to the frame portion so as to prevent the escape of poultry or cattle. This gate is usually supported by a durable fence post 6 driven substantially 65 into the ground so as to firmly support the post in a vertical position.

Referring now more particularly to the structure embodying my invention, the numeral 7 indicates a bracket member adapted 75 to be securely fastened to one of the vertical end beams of the gate. This bracket embodies a transverse bracket plate 8 apertured to receive suitable fastening bolts 9. As is obvious, with reference to Figure 1, 80 the bracket 7 is preferably secured to the central portion of the end gate beams. The body of the bracket 7 is preferably tapered in cross section and carries at its outer edge an enlarged sleeve 10 circular in cross section and provided with a longitudinal internally screw threaded bore therethrough. This sleeve is engageable with a suitable adjusting apparatus mounted on the fence post 6, as will be described more fully herein- 85 after.

Secured to the fence post 6 and extending vertically in spaced relation thereto is a longitudinal cylindrical casing 11 open at the ends and externally screw threaded. 95 The upper end of the casing is enclosed by a flanged cap 12 provided at its center with an opening about which is formed an inwardly extending guide sleeve 13, this cap being threadedly mounted on the casing 11. 100 The lower end of the casing is enclosed by a flanged cap 14 provided with an inwardly extending ring 15. Rotatably mounted in the center of the casing and held in position by the guide sleeve 13 and ring 15 is a longitudinal externally screw threaded shaft 16. The upper end of this shaft extends substantially above the casing and carries a hand wheel 17 adapted to permit convenient 105 rotation of the shaft. The intermediate sec- 110

tion of the shaft 16 is inserted through the threaded bore formed in the sleeve 10, so that rotary movement of the shaft will cause the bracket 7 to be elevated or lowered. 5 In order that the bracket may conveniently connect with the shaft 16, the casing 11 is provided with a longitudinal slot 18 so as to permit the reduced portion of the bracket body to be vertically movable therein. With 10 particular reference to Figure 2, it will be noted that the shaft 16 carries a collar 19 secured adjacent the upper end by a set screw or the like and adapted to contact with the lower extremity of the guide sleeve 13 so that 15 the shaft will be held against axial movement.

In order that the gate and adjustable mechanism may be readily swung in a horizontal arc, the casing carries a pair of 20 longitudinal plates 20 secured to the upper and lower caps by rivets or the like and extending toward the gate post. These plates 20 are rotatably secured upon angular brackets 21 secured in spaced relation to 25 the fence post 6, as will be apparent from Figures 1 and 2 of the drawing. The plates 20 are pivotally connected to the brackets 21 by means of bolts 22 extending through aligned openings formed in the 30 brackets and plates. This construction will permit the gate and adjustable support mechanism to be conveniently swung in an arc so as to open or close the gate to permit the passage of persons or vehicles.

35 It is evident, from the foregoing, that an adjustable gate supporting mechanism is provided, permitting the gate to be conveniently adjusted in a vertical plane when desirable. To elevate the gate, the hand 40 wheel 17 is turned by the operator in a clock-wise direction, causing the bracket 7 to be elevated in the casing and, of course, simultaneously raising the gate. The gate is lowered by reverse movement of the hand 45 wheel and shaft, this operation of course depending upon the manner of threading the shaft 16. This structure, while comparatively simple and durable of construction affords an adjustable support of efficient design permitting the gate to be retained in any desired position with comparatively little effort.

50 It is to be understood that the form of my invention herewith shown and described is to be taken as the preferred example of the same and that various changes as to the shape, size and arrangement of parts may be resorted to without departing from the spirit of the invention or the scope of the 55 subjoined claims.

60 Having thus described my invention, I claim:

1. An apparatus of the character described comprising a casing, a threaded 65 shaft rotatably mounted in the casing,

means for pivotally retaining the casing in position, and a bracket having a portion extending in the casing engageable with the shaft for vertical movement of the bracket. 70

2. An apparatus of the character described comprising a casing, a threaded shaft rotatably mounted in the casing, means for pivotally supporting the casing in vertical position, and a bracket having a portion extending within the casing threadedly engageable with the shaft so that the bracket may be movable longitudinally of the casing. 75

3. A gate supporting apparatus comprising a casing having a longitudinal slot 80 formed therein, a threaded shaft rotatably mounted in the casing, means for rotating the said shaft, a pair of plates secured to the extremities of the casing extending therefrom, angular brackets pivotally connected to the said plates, means for securing the brackets on a fence post, a bracket member adapted to be secured to a gate, the said bracket including a cylindrical portion 85 movable in the casing threadedly engageable with the shaft for adjustment of the gate. 90

4. A gate supporting apparatus comprising, in combination, a cylindrical casing having a longitudinal slot formed therein, 95 a threaded shaft rotatably mounted in the casing, means for retaining the threaded shaft in position, support plates secured to the extremities of the casing, angular brackets pivotally connected with the support plates, means for securing the said brackets upon a fence post, a gate bracket embodying a body portion, a plate having openings formed therein for connection with the gate, means for securing the 100 bracket upon a gate, a sleeve member formed on the outer portion of the bracket slidably movable in the casing, the said sleeve being provided with an internally 105 screw threaded bore engageable with the 110 shaft.

5. A gate supporting apparatus comprising, in combination, a cylindrical casing having a longitudinal slot formed therein, 115 a shaft rotatably mounted in the casing and projecting above the upper extremity, the said shaft being externally screw threaded, means for retaining the shaft in position in the casing, means for conveniently rotating the shaft, supporting plates secured to the 120 extremities of the casing, angular brackets pivotally secured to the supporting plates, means for securing the angular brackets upon a fence post, and a gate bracket including a body portion, an angular 125 bracket plate formed on one end of the body, means for securing the bracket plate upon a gate, a sleeve member formed on the opposite end of the body slidably in the 130 casing, the sleeve being provided with an

internally screw threaded bore engageable with the threaded shaft adapted to permit vertical adjustment of the gate.

6. In a gate hinge, a cylindrical casing having a longitudinal slot at one side thereof, a head on the lower end of said casing having a foot step bearing means centrally thereof, a head on the upper end of the casing having a bearing extending therethrough, a screw threaded shaft extending longitudinally of said casing and

journalized in said bearings, an operating head on said shaft, means for pivotally connecting the cylinder heads to a gate post, and a bracket including a cylindrical head fitted in said casing and having a threaded bore engaging on said screw and a member projecting through the slot and carrying means for attachment to a gate. 15

In testimony whereof I affix my signature.

HARRIS BURT HOLBROOK.
